UNITED STATES PATENT OFFICE.

JAMES H. BENSON, OF RINGSTED, IOWA, ASSIGNOR, BY MESNE ASSIGNMENTS, TO
LESTER B. OESTERN.

SHIM.

Application filed April 13, 1922. Serial No. 555,327.

To all whom it may concern:

Be it known that I, JAMES H. BENSON, a citizen of the United States, residing at Ringsted, in the county of Emmet and 5 State of Iowa, have invented certain new and useful Improvements in Shims, of which the following is a specification.

This invention relates to new and useful improvements in shims for taking up the 10 play between two parts or elements, the primary object of the invention being to provide a device of this character which can be easily inserted into a space to be filled without necessitating the removal or disturbance 15 of parts causing the space.

Another important object of the invention resides in the provision of a shim for bearings which is provided with means for detachable engagement with the bearings for 20 retaining the shim in its proper position.

Another object of the invention is to provide a device of the above mentioned character which is simple in construction, strong, durable and efficient in operation.

25 Other objects and advantages of the invention will become apparent during the course of the following description.

In the accompanying drawings forming a part of the description and wherein like numerals are employed to designate like parts 30 throughout the several views,

Figure 1 is a side elevation of the shim illustrating one use thereof,

Figure 2 is a transverse section on line 35 2-2 of Fig. 1 illustrating an end elevation of the shim,

Figure 3 is a horizontal transverse section of a bearing showing the shim attached thereto,

40 Figure 4 is a section through the shim, Figure 5 is a perspective view of the same.

In the drawing wherein for the purpose of illustration is shown the preferred embodiment of the invention, the numeral 6 45 designates a crank shaft center bearing to which the present invention is adapted to be applied although it will of course be understood that the invention is not limited to this specific use as its application as a shim 50 is readily perceived.

This main center bearing consists of a pair of sections 7 and 8, the former being supported by a depending bracket 9 as is customary in a well known type of motor vehicle. The lower section 8 or a cap of 55

the bearing is provided at opposite sides thereof with apertured ears 10 through which bolts 11 pass for securing the sections of the bearing around a portion of a crank shaft 12. It is well known that after continued use, the bearing and crank portions of the shaft become worn so that a space therebetween is eventually created so that the shaft has end play in the bearing thereby causing detrimental effects on various 60 parts of the engine of which the crank shaft forms a part. It is also well known that this end play of the crank shaft causes poor operation of the magneto as the magnets are caused to be spaced too far away from the 65 magneto coils to obtain the intense spark which is essential to the proper functioning of the engine.

In order to overcome these difficulties and to compensate for the wear between the 70 bearings and crank shaft without removing the engine from the vehicle or removing any of the parts which cause the play there between, I provide a shim which consists of a semi-circular flat plate 13 made of wear 75 resisting material, and provide the same with a convexo-concave inner edge 14 which is tapered or beveled as clearly seen in Fig. 4 so that the same is substantially wedge shaped. 80

In order to properly retain the shim in position it is provided with a pair of arms 15 which extend outwardly from opposite ends of the shim in opposite directions. These arms are bent as at 16 outwardly from the 85 shim, to extend at substantially right angles thereto. The free ends of these arms are provided with apertures by looping the same as at 17. In the present instance the arms 15 are provided by a stout piece of wire having 90 its intermediate portion attached to the arched portion of the shim plate. This intermediate portion of the wire is arcuated in the same direction as the inner edge of the shim so as to snugly fit around one end of 95 the bearing section 8. The ends of this wire are then bent or looped in the manner hereinbefore mentioned so that openings are provided for the passage of the bolts 11. 100

To apply the shim to a bearing, the bolts 11 are preferably removed and the shim plate is moved so that its beveled edge 14 engages between the bearings and the crank of the shaft so that it can be forced up into the space caused by wear between the parts. 110

When having thus positioned the shim, the loops 17 of the arms thereof will be in alignment with the apertured ears of the bearing section 8 so that the bolts 11 can be properly 5 assembled with the bearings to retain the two sections thereof in proper engagement, and at the same time the shim will of course be firmly held in proper position to take up the play between the bearing and the crank 10 shaft. By the particular construction of the shim it will be seen that the same can be easily assembled and associated with the main center bearing of the crank shaft without necessitating the removal of the engine 15 as is the customary practice at present when a play between the main center bearing and the crank shaft is to be remedied.

The foregoing description and accompanying drawings have reference to what might 20 be considered to be the approved or preferred form of my invention. I desire it to be understood that I may make changes in the construction, combination and arrangement of parts, materials, dimensions, etc. as 25 may prove expedient and fall within the scope of the appended claims.

Having thus fully described my invention what I claim is:—

1. A bearing shim comprising a half-washer, a pair of retaining arms extending 30 in opposite directions from the lower convex edge of said half-washer, said arms being bent to extend in diverging relationship in a plane at an angle to the plane of the shim, and the free ends of said arms being bent to 35 form eyelets.

2. The combination with a bearing having removable halves, and bolts to secure the halves together, of a shim comprising a half-washer, a pair of retaining arms extending 40 from the lower arcuate edge of said half-washer in opposite directions and in a plane parallel to the half-washer, said arms adjacent the washer being bent upwardly then in a plane at an angle to the half-washer, said 45 arms being arranged in diverging relationship, and the free ends of said arms being bent to form eyelets to be clamped between the heads of the bolts and the lower half of the bearing.

In testimony whereof I affix my signature in presence of two witnesses.

JAMES H. BENSON.
